US0D1043193S

(12) United States Design Patent (10) Patent No.: US D1,043,193 S
(45) Date of Patent: * Sep. 24, 2024

(54) STORAGE BOX

(71) Applicant: Yunchu Xu, Guangdong (CN)

(72) Inventor: Yunchu Xu, Guangdong (CN)

() Term: 15 Years

(21) Appl. No.: 29/939,579

(22) Filed: Apr. 28, 2024

Related U.S. Application Data

(62) Division of application No. 29/926,574, filed on Jan. 31, 2024.

(51) LOC (14) Cl. 06-04

(52) U.S. Cl.
